(57) **CLAIM**

The ornamental design for a fluorescent lamp, as shown and described.

DESCRIPTION

FIG. 1 is a front view of a fluorescent lamp of the present invention, wherein the rear view is a mirror image thereof;

FIG. 2 is a top view thereof;

FIG. 3 is a right side view thereof, wherein the left side view is a mirror image thereof; and,

FIG. 4 is a bottom view thereof.

The ornamental design which is claimed is shown in solid lines in the drawings. Any broken lines in the drawings are for illustrative purposes only and form no part of the claimed design.
